R. L. QUASS

PARTY LINE TELEPHONE EXCHANGE SYSTEM

Filed Dec. 22, 1920

Inventor:
Ralph L. Quass
by E.R. Nowlanatty

UNITED STATES PATENT OFFICE.

RALPH L. QUASS, OF HAWTHORNE, NEW JERSEY, ASSIGNOR TO WESTERN ELECTRIC COMPANY, INCORPORATED, OF NEW YORK, N. Y., A CORPORATION OF NEW YORK.

PARTY-LINE TELEPHONE-EXCHANGE SYSTEM.

Application filed December 22, 1920. Serial No. 432,471.

To all whom it may concern:

Be it known that I, RALPH L. QUASS, a citizen of the United States, residing at Hawthorne, in the county of Passaic, State of New Jersey, have invented certain new and useful Improvements in Party-Line Telephone-Exchange Systems, of which the following is a full, clear, concise, and exact description.

10 This invention relates to machine switching telephone exchanges employing party line working, and more particularly to that type of system wherein the subscribers on the party lines signal other parties on the same line by means of a special code which causes ringing relays at the exchange to selectively ring back on the line and ring the bells at both the calling and called stations. In this type of system, the calling party 15 hangs up his receiver after having dialed the digits of the code, such replacement of the receiver causing the starting of the ringing operation.

Such a system is shown for example in 20 Patent No. 1,158,221 of October 26, 1915, to H. Hovland.

It is the object of this invention to provide a system which will accomplish the same results with less equipment than heretofore 25 necessary.

In the patent referred to, a given level of a selector is used for these revertive calls. Each of the trunks from this level terminates in a so-called frequency selector. Each of 30 these frequency selectors is provided with ringing relays and associated apparatus for picking out the two kinds of current for selectively ringing the bells of the calling and called lines alternately.

35 In the arrangement of this invention instead of providing a frequency selector and associated apparatus for each trunk in the level a smaller number is provided and the circuit is so arranged that the selector will 40 not seize a trunk unless the test indicates that not only the trunk is idle but that an idle frequency selector adapted to serve the same is also idle. Inasmuch as the period during which a frequency selector is used is 45 only a small part of the period during which a trunk is used in a given connection, it is evident that the number of frequency selectors may be smaller than the number of trunks.

Referring to the drawing in which Fig. 1 50 illustrates the preferred embodiment of my invention, only the brushes and cooperating terminals of the line switch LS and first selector FS are shown, since these switches may be the same as those shown in the Hovland patent referred to. It will be understood that both the trunks shown are located in the same level, which level is allotted to revertive signalling. As stated, the party line subscribers in making revertive calls 55 use a special numbering system different from that in making non-revertive calls. Fig. 2 is a chart showing the combinations of current sent out in each position of the frequency selector switch.

The invention will be more readily understood from a detailed description of the operation of the system. The removal of the receiver at substation 1 causes the line switch to operate to extend the party line to the 70 first selector FS. This first selector is then set by means of the sender S to the level allotted to revertive calls. It then automatically hunts over the trunks in this level, and upon reaching an idle trunk seizes the same. 75 The seizure of this trunk which we shall presume to be the upper trunk shown in the drawing, operates the stepping relay B, which in operating energizes slow relay C. Relay C in attracting its outer left armature 80 grounds test multiple 100 of the seized trunk to cause the same to test busy and at its inner armature operates relay D over a circuit including the right-hand armature and back contact of relay E, outer left armature of relay D' of the lower trunk to ground at the outer left armature and front contact of slow relay C. Relay D 85 in its outer left armature applies ground to the test multiple 101 of the other 90 trunk having access to this frequency selector. The receipt of the impulses corresponding to the second digit of the code, causes the relay B to transmit impulses from its armature and back contact over the 95 inner right armature and front contact of relay D, slow relay F, inner left armature and back contact of relay M, motor magnet MM of the frequency switch, resistance 102 to battery. The arms T, R, PU, 100 L and Rel are thus advanced over their terminals. Upon the beginning of the impulses, the relay F closes a circuit to operate

105

relay J, this circuit including the armature and back contact of relay 108. Relay J in attracting its outer right armature opens the restoring circuit of the motor magnet, and in attracting its inner right armature closes the starting circuit which causes the ringing machine 103 and interrupter 104 to operate. Upon the cessation of the impulses the slow relay F releases, removing the short-circuit to ground at the armature of relay 108 from about the winding of relay K. Relay K now operates in series with relay J; free pole of battery, relays J and K, inner left armature and front contact of relay J, conductor 105, inner left armature and front contact of relay D, ground at the armature and back contact of relay 108.

The calling subscriber now hangs up his receiver, deenergizing relay B, but before the slow relay C can release, a substitute circuit therefor is closed at the right armature and front contact of relay A which energizes upon the release of relay B over the following circuit: free pole of battery, relay A, outer right armature and front contact of relay D, outer right armature and front contact of relay M, outer left armature and front contact of relay J, conductor 106, inner right armature of relay D to ground at the back contact of relay B. Assume that the subscriber at substation 1 has called subscriber at substation 4. In order to ring the bell at these stations, positive current would have to be applied over the ring side, and negative current over the tip side of the line. Referring to the wiring of the frequency selector, it will be seen that in order to transmit this combination of currents six impulses would have to be sent to set the frequency switch in its sixth position. This is evident from an inspection of the diagram shown in the lower left corner of the drawing. When the relay K operated, it energized relay M. This relay in attracting its outer left armature connects interrupting machine 104 to the pull up arm 107, which arm is now on its sixth contact. In position 6, the arm L closes a circuit to energize relay H, this circuit including the inner left armature and front contact of relay M, and the motor magnet 102 which is marginal does not operate in this circuit. Due to the operation of relay H and arm PU being in its sixth position, the relays G and P operated. Each time the interrupting machine 104 reaches an insulated segment, these two relays are released. The simultaneous energization of these relays, G and P, causes positive current from generator 103 to flow over the ring side of the line to operate the bell at substation 1 only, and each time these relays are released, negative current is transmitted over the tip side of the line to operate the ringer at substation 4 only. The ringing system employed is

the same as shown in Patent No. 768,272, to T. C. Drake, issued August 23, 1904, known as superimposed ringing. The relays G and P will continue to operate to ring the bells at the calling and called substations 1 and 4 alternately, until the called subscriber at substation 4 removes his receiver, causing the operation of the ringing cut-off relay 108. This relay in attracting its armature releases relays J and K. Relay K in turn releases relay M. Relay J releasing its outer left armature, releases relay A which again bridges relay B across the calling line. This relay in attracting its armature closes the substitute circuit for the slow relay C to prevent premature release. The release of relay A cuts off the ringing current. The subscribers may now converse, current being supplied to both transmitters over the windings of the relay B.

Relay K is slow to release and consequently holds relay M operated a short time after relay J operates due to relay 108 operating upon response of the called party. Consequently, the following circuit is closed for relay E; free pole of battery relay E, its left contact, conductor 110, right armature and front contact of relay M, outer left armature and back contact of relay J to ground at the armature and back contact of relay B. Relay E in attracting its armature locks itself up to ground at the outer left armature and front contact of relay C, and in attracting its right armature opens the circuit which has been holding relay D energized. Relay D in retracting its outer left armature closes a break in the circuit of relay D' which belongs to the lower trunk, restoring the control of the frequency selector to the lower trunk. The function of the relays D and D' which are respectively individual to the upper and lower trunks, is to prevent interference with the frequency selector by the one trunk while it is being used by the other.

Upon the termination of the conversation, the subscribers replace their receivers which causes the release of relay B, which opens the circuit of relay C. This relay in releasing removes ground from the multiple 100 and the sleeve wire leading back to the first selector and line switch, causing the release of the same, as described in the said Hovland patent. The retraction of the outer left armature of relay D removes ground from the multiple 101 of the lower trunk to render the same accessible to other first selectors.

The first six terminals of the frequency selector give the required combination of current to enable any substation to signal any other and itself. The last four terminals are used to ring back on the line for bell adjustment, that is to say, when seven impulses are sent only the bell of the call-

ing station will be operated upon the replacement of its receiver, etc. The release of the outer right armature of the relay

5 J closes a self-interrupting circuit from motor magnet MM. This circuit includes the arm Rel of the frequency selector thus causing the frequency selector to step around to its normal position.

It will be seen from the foregoing that 10 by virtue of the present arrangement a calling subscriber merely has to remove his receiver and dial a certain code which will cause one of a number of frequency selectors, less in number than the number of 15 trunks in the level, to select the two desired ringing generators and then upon replacing the receiver upon the hook his bell and the bell of the desired station is rung, the response of the called party causing 20 the ringing to cease, thus indicating to him that the called subscriber has answered. The frequency selector is only removed from access to the other trunk while it is actually ringing the stations, and immediately 25 upon the response of the called party reverts to the use of the other trunk. While a frequency selector for each pair of trunks is shown, that is, five for a level of ten trunks, it will be understood that the invention 30 is not to be so limited. Fewer or more frequency selectors could be provided as the traffic requires.

What is claimed is:

1. In a telephone system, a party line 35 having substation ringers connected thereto, a calling terminal for said line, trunks at the exchange, ring back apparatus at the exchange common to said trunks, means for extending a connection from said line to 40 said ring back apparatus over said calling terminal and one of said trunks and for associating said ring back apparatus with the seized trunk, means for operating said apparatus to project ringing current back 45 over the said calling terminal to the calling line to enable one party to selectively signal another party on the same line, and means operated by the response of one of the 50 parties for causing said ring back apparatus to revert to common use.

2. In a telephone system, a party line 55 having substation ringers connected thereto, a calling terminal for said line, trunks at the exchange, ring back apparatus at the exchange common to said trunks, means for extending a connection from said line to 60 said ring back apparatus over said calling terminal and one of said trunks and for associating said ring back apparatus with the seized trunk, means operated by the taking 65 of the ring back apparatus for use for causing another trunk having access to said ring back apparatus to test busy, and means for operating said apparatus to project ringing current back over the said calling terminal 70 to the calling line to enable one party to selectively signal another party on the same line, and means operated by the response of the calling party for causing said ring back apparatus to revert to common use, and for 75 removing the artificial busy condition from the other said trunk.

3. In a telephone system, a party line having substation ringers connected thereto, a calling terminal for said line, trunks at the

terminal to the calling line to enable one party to selectively signal another party on the same line.

3. In a telephone system, a party line having substation ringers connected thereto, a calling terminal for said line, trunks at the exchange, ring back apparatus at the exchange common to said trunks, means for extending a connection from said line to 70 said ring back apparatus over said calling terminal and one of said trunks and for associating said ring back apparatus with the seized trunk, means operated by the response of the called party for causing said ring back apparatus to revert to common 75 use, and means for operating said apparatus to project ringing current back over the said calling terminal to the calling line to enable one party to selectively signal another party on the same line.

4. In a telephone system, a party line having substation ringers connected thereto, a calling terminal for said line, trunks at the exchange, ring back apparatus at the exchange common to said trunks, means for 80 extending a connection from said line to said ring back apparatus over said calling terminal and one of said trunks and for associating said ring back apparatus with the seized trunk, means operated by the calling 85 party for causing said ring back apparatus to select currents of different frequency to selectively ring both the calling and called stations, means operated by the replacement of the receiver by the calling party for causing 90 the application of the ringing current, and means actuated by the response of the called party for cutting off the ringing current, and for releasing the ring back 95 apparatus for common use.

5. In a telephone system, a party line having substation ringers connected thereto, a calling terminal for said line, trunks at the exchange, ring back apparatus at the exchange common to said trunks, means for 100 extending a connection from said line to said ring back apparatus over said calling terminal and one of said trunks and for associating said ring back apparatus with seized trunk, means operated by the taking 105

of the ring back apparatus for use for causing another trunk having access to said ring back apparatus to test busy, and means for operating said apparatus to project ringing current back over the said calling terminal 110 to the calling line to enable one party to selectively signal another party on the same line, and means operated by the response of the calling party for causing said ring back apparatus to revert to common use, and for 115 removing the artificial busy condition from the other said trunk.

6. In a telephone system, a party line having substation ringers connected thereto, a calling terminal for said line, trunks at the

4

exchange, ring back apparatus at the exchange common to said trunks, means for extending a connection from said line to said ring back apparatus over said calling terminal and one of said trunks and for associating said ring back apparatus with the seized trunk, means controlled by the calling party for causing said ring back apparatus to select currents of different character to 10 selectively ring both the calling and called stations, means operated by the replacement of the receiver by the calling party for causing the application of the ringing current, and means actuated by the response of the 15 called party for cutting off the ringing current, and for releasing the ring back apparatus for common use.

7. In a telephone system, a party line having substation ringers connected thereto, 20 a calling terminal for said line, trunks at the exchange, ring back apparatus at the exchange common to said trunks, means for extending a connection from said line to said ring back apparatus over said calling terminal and one of said trunks, and for associating said ring back apparatus with the seized trunk, means controlled by the calling party for causing said ring back apparatus to select ringing current to selectively ring

both the calling and called stations, means 30 operated by the replacement of the receiver by the calling party for causing the application of the ringing current, and means actuated by the response of the called party for cutting off the ringing current, and for 35 releasing the ring back apparatus for common use.

8. In a telephone system, a party line having substation ringers connected thereto, 40 a calling terminal for said line, a plurality of trunks, means for automatically extending a calling line to an idle trunk, ring back apparatus, automatic means actuated upon the seizure of said trunk for connecting said ring back apparatus to the seized trunk and 45 for rendering it unselectable, means for operating said apparatus to project ringing current back over said terminal to the calling line to enable one party to signal another party on the same line, and means for 50 automatically disconnecting said ring back apparatus upon the response of the called party and for again rendering the same selectable.

In witness whereof I hereunto subscribe 55
my name this 18th day of December, A. D.
1920.

RALPH L. QUASS.
